WINDOW LOCK

Filed Nov. 13, 1928

BY *Carmine Vitale*
Solomon Blachky
ATTORNEY

UNITED STATES PATENT OFFICE

CARMINE VITALE, OF NEW YORK, N. Y.

WINDOW LOCK

Application filed November 13, 1928. Serial No. 319,056.

This invention relates generally to windows and has more particular reference to a novel lock for holding windows in closed position or partially open positions.

5 The invention has for an object the provision of a device of the class mentioned which is of simple durable construction, desirable in use and efficient in action, and which can be manufactured and sold at a reasonable cost.

10 The invention proposes the use of a lock strip with struck out tongues, secured upon a window frame and the tongues being engaged by a lock foot attached on a shank 15 slidably mounted in a bushing provided with external threads engaged in a threaded boss supported upon one of the sashes of the window. The shank is provided at its free end with a handle engaging against the 20 bushing. Preferably the point of attachment upon the sash should be on the top edge of the inner sash at one end thereof or at both ends, or, and on the inner face of the outer sash.

25 For further comprehension of the invention, and of the objects and advantages thereof, reference will be had to the following description and accompanying drawings, and to the appended claim in which the 30 various novel features of the invention are more particularly set forth.

In the accompanying drawing, forming a material part of this disclosure:

Fig. 1 is a perspective view of a window 35 constructed according to this invention.

Fig. 2 is a horizontal sectional view, taken on the line 2—2 of Fig. 1.

Fig. 3 is a vertical sectional view, taken on the line 3—3 of Fig. 2.

40 Fig. 4 is a side elevational view of Fig. 3.

Fig. 5 is a perspective view of the lock strip used in the device.

Fig. 6 is a horizontal sectional view, taken on the line 6—6 of Fig. 5.

45 Fig. 7 is a view similar to Fig. 2, but showing the device in a locked position.

Fig. 8 is a view similar to Fig. 3, but disclosing a modification thereof.

Fig. 9 is a fragmentary vertical sectional 50 view, taken on the line 9—9 of Fig. 8.

The reference numeral 10 indicates generally a wall seen from the inner side and having a window consisting of a window frame 11, an inner sash 12, and an outer sash 13. The top edge of the inner sash is indicated by numeral 14.

55 A lock strip 16 provided with a plurality of lock tongues 17 is secured by screws 18 upon the window frame 11, preferably in a vertical groove 19 formed in the window frame. The lock tongues 17 are preferably struck out of the material of the lock strip.

Secured on the top edge 14 of the inner sash 12 is a base 20. This base is provided with lugs 21 thru which screws 22 pass for producing the securing action. A vertical wall 23 is integral with the base 20 and is formed with a boss 24 provided with internal threads 25. An external threaded bushing 26 engages the threads 25 and is provided with an enlarged knurled head 27. A shank 28 is slidably and rotatively mounted within the bushing 26 and has a square head 29, which also serves as a handle, attached at one end the head 29 engages against the head 27, while a lock foot 30 is attached on the other end of said shank. This lock foot is of small width and of greater height as may be gathered from Figs. 2 and 4, and is eccentrically mounted upon the shank 28. 70 The base 20 is formed with a groove 20^a for receiving the lock foot 30 and holding it in a retracted unlocked position, as indicated in broken lines in Fig. 4.

75 Normally the lock foot 30 stands vertically in the groove 19 so that the window sash may be raised and lowered without any interference in any raised or lowered position of the window sash. The handle 29 may then be rotated to move the lock foot 30 thru an angle of 90 degrees for engaging said lock foot into one of the lock tongues 17. Then the knurled head 27 may be rotated for advancing the bushing 26 outwards so as to push against the handle 29 80 sliding the shank 28 outwards and causing the lock foot 30 to firmly engage against the lock tongue 17. Fig. 7 illustrates this 85 locked position of the device.

90 It should be noted that the window sash 100

is now locked against being moved. Dot-dash line 32 in Fig. 1 indicates that a duplicate of the device mounted on the top edge of the inner sash, may be mounted upon the inner face of the outer sash and is operable in the same manner for locking the outer sash in any desired position.

In the modified form of the device illustrated in Figs. 8 and 9 a base 20' has been illustrated with a dove-tail groove 33 engaged by a dove-tail tongue 34 integral with a vertical wall 23'. This vertical wall 23' is provided with a boss 24 for supporting the bushing 26 and the slideable shank 28. Standards 35 project from the base 20' and a screw 36 is rotatively mounted in the standards. This screw has a square end 37 for engagement by a turning tool, and the main portion of the screw threadedly engages the wall 23'. The screw 36 may be rotated for sliding the vertical wall 23' forwards or rearwards on the base 20' so that the position of the lock foot 30 may be adjusted to engage the lock strip of windows 25 in which the groove 19 is of greater or smaller depth.

While I have shown and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:—

In combination with a window having a frame and a sash movable therein, a dovetailed tongue mounted in a dovetailed groove on the sash, a tubular boss integral with said dovetailed tongue, said tubular boss being formed with a threaded barrel open at both ends, a threaded shank engaging in the barrel and extending beyond the barrel at both ends, a manipulating handle attached at one end of the shank, a lock foot attached at the other end, a lock tongue engaged on the frame for receiving the lock foot, and means for adjusting said dovetailed tongue in the groove for moving the boss to a convenient distance from the lock tongue for permitting the shank to be operated for securing the lock foot in locked relation with said tongue.

In testimony whereof I have affixed my signature.

CARMINE VITALE.
